Primary Examiner — Kelley Donnelly(74) *Attorney, Agent, or Firm* — Leanne Taveggia Farrell; Westman, Champlin & Koehler, P.A.(57) **CLAIM**

The ornamental design for a bin, as shown and described.

DESCRIPTION

FIG. 1 is a perspective view of a bin showing my new design; FIG. 2 is a side view thereof, the opposing side being a minor image;

FIG. 3 is a front view thereof;

FIG. 4 is a top view thereof;

FIG. 5 is a perspective view of a second embodiment thereof; FIG. 6 is a side view of FIG. 5, the opposing side being a mirror image;

FIG. 7 is a front view of FIG. 5; and,

FIG. 8 is a top view of FIG. 5.

The broken lines shown in the drawings are included for purposes of illustrating portions of the bin and form no part of the claimed design.

1 Claim, 6 Drawing Sheets(56)
